YARN WINDING DEVICE

Albert W. Keight, Cumberland, Md., assignor to
Celanese Corporation of America, a corpora-
tion of Delaware

Application July 1, 1942, Serial No. 449,207

5 Claims. (Cl. 242—43.5)

This invention relates to a twisting and winding apparatus for twisting and winding into pinn, cop or other headless package yarns or threads, especially those containing a derivative of cellulose or other synthetic yarn made by continuous spinning processes.

Headless packages have heretofore been formed by superimposing two motions on the guide directing the yarn on to the package, namely, an up and down traversing or "chasing" motion and a slow progressive feed or lift for building the package, which moves up only once during the filling of the package. Such packages cannot economically be dressed because any dirt on the bottom layers of the package necessitates complete backwinding to clean up the yarn. The present invention overcomes this disadvantage by superimposing two motions, namely, a chaser motion similar to those of the prior devices and a separate builder motion that raises and lowers at any desired rate. For instance, the chaser mechanism may move up and down 10 times a minute and the builder mechanism reciprocate once in 5 minutes and a total of 20 times to fill a package. As the entire package is covered with a layer of yarn every 5 minutes, with the above timing of motions, it can be dressed by removal of one layer, or the amount applied in 5 minutes.

Another advantage of the present invention is the simplicity of design and relation of parts which make for economy of construction.

A still further advantage of the present invention is that any package on the metier or spinning machine can be doffed and restarted at any time without a resetting of any mechanical parts, thereby increasing the number of units which can be taken care of by the operator.

Other advantages and objects of the invention, together with certain details of construction and combinations of parts, will appear from the following description and from the drawings.

In the drawings there is shown one embodiment of my invention adapted especially to form headless packages at an artificial silk metier. The invention may, however, be employed on any winding or packaging machine.

Fig. 1 is a front elevation of a section of a packaging device showing the driving mechanism therefor.

Fig. 2 is a detail view of a part of the driving mechanism shown in Fig. 1.

Fig. 3 is a cross-sectional view of one of the packaging elements taken on the line 3—3 of Fig. 1.

Fig. 4 is a cross-sectional view taken on the line 4—4 of Fig. 3, and

Fig. 5 is a cross-sectional view taken on the line 5—5 of Fig. 3.

Like reference numerals designate like parts throughout the several views of the drawings.

As stated above, the invention relates to a mechanism or device for building a headless package, i. e., a cop or pinn, said device being applicable for attachment directly to artificial silk spinning cabinets, as well as other winding and packaging devices. It is applicable to building packages much larger than heretofore possible, say, from 700 to 1400 or more grams. Referring particularly to Fig. 1 of the drawings, spindle assemblies 1, each shown carrying a package of yarn 2, are arranged in a row along the front of the metier, the frame of which is generally indicated by the reference numeral 3. The package of yarn is built by the superimposing of two motions, the motion produced by the reciprocation of the ring rail 4 and the motion produced by the reciprocating of the spindle 1 itself. The package produced is of the headless type having two tapered ends and a cylindrical body portion. The ring rail 4 has a throw of substantially the cylindrical portion of the package while the spindle reciprocates about the length of one tapered portion. This superimposing of the chaser motion and builder motion builds a package of layers of yarn, each layer substantially covering the preceding layer.

The chaser motion is provided by ring rail 4 through main drive shaft 5 in the following manner: a fast and loose belt arrangement, comprising pulleys 6 driven by main shaft 5 connected by belt 6' to pulleys 7, drives a gear 8. The belts 9 which drive spindles 1 may also be driven by main shaft 5. The gear 8 meshes with and drives a gear 11 mounted on one end of a shaft 12. A worm gear 13 is fixed to the other end of shaft 12, which worm gear meshes with and rotates a gear 14 attached at one end of a shaft 15. At the other end of shaft 15 is mounted a heart-shaped cam 16 which is adapted to act against a cam follower 17 mounted for free rotation on an arm 18 (Fig. 1) pivoted at 19 on a boss 20 on main frame 3. The free end of arm 18 is adapted to receive one end of a connecting rod 21.

In order to adjust the length of the throw of connecting rod 21, the connection between arm 18 and connecting rod 21 is made adjustable. To this end, arm 18 is provided with a slot 22 in which is mounted a stud shaft 23 on which con-

necting rod 24 is journaled. The stud shaft may be held in any desired position in slot 22 by any suitable means, such as lock nuts (not shown). The other end of connecting rod 24 is attached to a collar 25 fastened to a rod 26 which is caused to reciprocate by the movement of connecting rod 24, as will appear more fully hereinafter. The reciprocating rod 26 is adapted to move through and be guided by apertured lugs 28 spaced at intervals along the frame of the twisting and winding machine.

At suitable intervals along, or at each end of, the reciprocating rod 26, depending upon the number of spindles and/or the length of the machine, are fixed collars 27, to each one of which is attached one end of a flexible cable or rope 28. The flexible cable is passed over a grooved idler pulley 29 and fixed to a lug 30 on a collar 31 adapted for sliding movement along a vertical bar 32. Each collar 31 has attached thereto a reciprocating lifting arm 33 which is guided in its vertical path by brackets 34. On the upper ends of lifting arms 33 is carried the ring rail 4 which is provided with a ring 35 for each spindle. The rings 35 may be equipped with a traveler or flyer in the usual manner.

The upon and down movement of the ring rail, or chaser motion, is usually relatively rapid, being on the order of from 5 to 20 strokes per minute. The length of the stroke is about equal to the length of the cylindrical section plus one tapered section of the package being produced. As is well understood in the art, the shape and size of the cam 16 governs the speed of the traverse and the shape of the yarn package. The shape and size of this cam may be varied to produce yarn packages of different configuration.

Superimposed upon the chaser motion is a builder motion, i. e., a slower motion imparted to the spindles which effects a relative movement of the yarn package being formed with respect to the ring rail 4. This builder motion is effected by mounting a sprocket wheel 36 on shaft 12 which is adapted to drive a sprocket wheel 37 by means of a chain 38. The sprocket wheel 37 is attached to and drives a shaft 39 of a variable speed reducing unit 41 on the output, or slow speed, shaft 42 of which is fixed a cam 43. This cam 43 operates against a cam follower 44 journaled in the lower end of a vertical rod 45 adapted to be reciprocated by cam 43 through guides 46 and 47. A portion of the rod 45, intermediate its ends, is formed into, or may have attached thereto, a rack 48 which meshes with and is adapted to rotate a pinion 49 fixed to a shaft 51 extending horizontally across the width of the machine. The shaft 51 is supported at intervals in brackets 52 mounted on a cross-piece 53 of the machine frame. Pinion gears 54 are fixed to shaft 51 at points opposite each spindle assembly. Each pinion gear is adapted to mesh with a rack 55 mounted on the bolster 56 of the spindle assembly in a manner described below.

The spindle assemblies preferably work in housings carried by cross-piece 53. To this end U-shaped lugs 57 are attached to and extend in a horizontal plane from cross-piece 53. A cylinder 58 is carried by each lug, the cylinder being provided at its top with a flange 59 adapted to be seated on the lug 57. The lower portion of 70 the cylinder is threaded on its outer surface as shown at 61 to receive internally threaded rings 62 and 63 for the purpose of securely fastening the cylinder 58 in position on the lug 57.

A slot 64 is provided in the cylinder 58 to al-

low the pinion 49 to extend therein to mesh with the spindle rack 55. The inner face of the cylinder 58 is formed into, or has attached thereto, a split sleeve 65 that provides a bearing surface for an internally threaded tube 66 attached to the threads on the well 67 of the bolster 56. The slot in sleeve 65 is wide enough to allow room for the spindle rack 55 that is directly attached to the tube 66 and thus to the bolster 56 of the spindle.

The spindle assembly may be of any suitable manufacture and comprises generally the well 67 for holding a supply of oil and steps or bearings for the spindle, which is formed with a whorl 68 for frictional engagement with the drive belt 9, a shoulder 69 for supporting the base 71 of a core 72 on which the yarn is wound and a blade 73 for aligning the said core. The core 72, in accordance with the present invention, may be a tube without flanges at the base or head, thus greatly reducing the cost of packaging yarn. The invention permits the employment of the cheapest type of core and it can be adapted to most existing machinery. The invention permits of the use of smaller rings on the ring rail for a comparative weight of yarn per package, thus allowing and making a greater clearance for handling resulting in less yarn soilage and damaged windings due to bumping the package in doffing operations. This invention eliminates traverse setting and thus a number of defects due to bad traverses.

Since this builder motion derives its power from shaft 12, which derives its power from shaft 5, it is in timed relation with the chaser motion. The two motions, however, must not be in phase but must be so adjusted that they do not synchronize, that is, the number of revolutions that primary cam 16 makes per unit of time must not be a multiple of the number of revolutions that secondary cam 43 makes per unit of time. The ring rail should be in a different position each time the spindle reaches its highest point, otherwise the package would require a head or flange thereon.

Packages formed by the device constructed in accordance with this invention and mounted directly on a cabinet, producing cellulose acetate yarn by the dry method of spinning, may be used without further processing in warp knitting, hose knitting, circular knitting and looms. The large size package built without a head eliminates coning and cheesing operations for many purposes where such steps were formerly necessary, such as in warping and warp knitting.

Another advantage of the type of package produced in accordance with this invention is that the yarn on the package dries uniformly. In the spinning of the yarn by the continuous process, some solvent remains in the yarn when wound on the package, and slight changes occur in the drying of the yarn depending upon whether the layers are exposed or covered up. In the type of package using the slow progressive feed, i. e., the one builder motion, certain layers are uncovered during the complete winding of the package and the exposed ends show a definite defect in the fabric because of difference in drying or discharge of solvent vapors.

The invention is applicable to substantially all packaging devices that now employ a ring rail traverse or cap spinning traverse. It may therefore be employed in the production of all the artificial yarns such as those made from or containing organic derivatives of cellulose such as

the organic acid esters of cellulose and cellulose ethers. Examples of organic acid esters of cellulose are cellulose acetate, cellulose aceto-butyrate, cellulose formate, cellulose butyrate and cellulose propionate, while examples of cellulose ethers are methyl cellulose, ethyl cellulose and benzyl cellulose. It may also be employed in the production of yarns of regenerated or reconstituted cellulose and yarns of the linear polymer of amides, polyamides, etc., with compounds having two or more reactant groups such as halogens, carboxyl, sulphonate, etc.

It is to be understood that the foregoing detailed description is given merely by way of illustration and that many variations may be made therein without departing from the spirit of this invention.

Having described my invention, what I desire to secure by Letters Patent is:

1. In a device for producing yarn packages of the headless type, the combination with a spindle, means for driving the spindle and a traverse ring rail, of means for reciprocating the ring rail to produce a chaser motion and means including a tube mounted on said spindle, a rack carried by said tube, a sleeve providing a bearing surface for said tube having a slot therein, a pinion projecting through said slot and meshing with said rack and means for driving the pinion to produce a builder motion superimposed upon said chaser motion.

2. In a device for producing yarn packages of the headless type, the combination with a spindle, means for driving said spindle and a traverse ring rail, of means including a cam and a connecting rod operated thereby for reciprocating said ring rail to produce a chaser motion, and means including a second cam and a rack and pinion operated thereby for reciprocating said spindle to produce a builder motion superimposed upon said chaser motion.

3. In a device for producing yarn packages of

the headless type, the combination with a spindle, means for driving said spindle and a traverse ring rail, of means including a cam and a connecting rod operated thereby for reciprocating said ring rail to produce a chaser motion, means including a second cam and a rack and pinion operated thereby for reciprocating said spindle to produce a builder motion superimposed upon said chaser motion, and means including a speed reducing unit for operating one of said cams at a greater speed than the other of said cams.

4. In a device for producing yarn packages of the headless type, the combination with a spindle, means for driving said spindle and a traverse ring rail, of means including a cam and a connecting rod operated thereby for reciprocating said ring rail to produce a chaser motion, and means for reciprocating said spindle to produce a builder motion superimposed upon said chaser motion, said means comprising a rack on said spindle, a pinion adapted to cooperate with said rack to reciprocate said spindle, a shaft on which said pinion is fixed, and a rotatable cam for causing the rotation of said shaft and pinion.

5. In a device for producing yarn packages of the headless type, the combination with a spindle, means for driving said spindle and a traverse ring rail, of means including a cam and a connecting rod operated thereby for reciprocating said ring rail to produce a chaser motion, means for reciprocating said spindle to produce a builder motion superimposed upon said chaser motion, said means comprising a rack on said spindle, a pinion adapted to cooperate with said rack to reciprocate said spindle, a shaft on which said pinion is fixed, and a rotatable cam for causing the rotation of said shaft and pinion, and means including a variable speed unit for operating one of said cams at a greater speed than the other of said cams.

ALBERT W. KEIGHT.
